UNITED STATES PATENT OFFICE.

PARK G. PAIGE, OF AUSTIN, NEBRASKA.

SNOW-PLOW.

1,172,305.

Specification of Letters Patent. Patented Feb. 22, 1916.

Application filed April 14, 1915. Serial No. 21,318.

To all whom it may concern:

Be it known that I, PARK G. PAIGE, a citizen of the United States, residing at Austin, in the county of Sherman and State of Nebraska, have invented a new and useful Snow-Plow, of which the following is a specification.

This invention relates to machines designed for removing snow from roads, one 10 of the objects of the invention being to provide a machine of this character having improved means for adjusting the road engaging blades both vertically and angularly.

With the foregoing and other objects in 15 view which will appear as the description proceeds, the invention resides in the combination and arrangement of parts and in the details of construction hereinafter described and claimed, it being understood that 20 changes in the precise embodiment of the invention herein disclosed, can be made within the scope of what is claimed, without departing from the spirit of the invention.

25 In the accompanying drawings the preferred form of the invention has been shown.

In said drawings:—Figure 1 is a plan view of the machine designed for use as a snow plow. Fig. 2 is a side elevation thereof. Fig. 3 is an enlarged vertical transverse section on line A—B Fig. 1. Fig. 4 is a perspective view of the adjustable head of the machine, the blades being removed therefrom.

35 Referring to the figures by characters of reference 1 designates a beam provided at one end with a cross head 2 provided with braces 3 whereby it is held against movement relative to the beam 1, this cross head 40 2 being provided with casters 4 connected to the end portions thereof. Each caster has an outstanding ear 5 adapted to receive a locking pin 6 slidably mounted within supporting brackets 7 extending from the cross head. When the locking pin is in engagement with the ear 5, the caster 4 is held against free rotation relative to the head but, when the pin 6 is removed, said 45 caster can rotate freely.

50 A clevis 8 is connected to the middle portion of the cross head 2 and is adapted under certain conditions, to engage the middle portion of a draft bar 9 to the ends of which are connected links 10. Each link 55 has a whiffletree 11 secured to it and each whiffletree is preferably provided with two

swingletrees 12. The two whiffletrees are located beyond opposite sides of the beam 1 so that by means of the draft mechanism described, four horses can be used, two at 60 each side of the beam 1.

Another clevis 13 is secured to the beam 1 at a point removed from the clevis 8 and is engaged by a lever 14 to which are secured neck yokes 15. It is to be understood that 65 with the draft mechanism arranged as shown and described, the casters will be located at the rear end of the machine. However, the levers 9 and 14 can be interchanged so that the swingletrees 12 will be in the positions occupied by the neck yokes 15 in Fig. 1, while said neck yokes will be in the positions occupied by the swingletrees in said figure. With the parts thus rearranged, the casters 4 will be at the front end of the 75 machine. This last arrangement is especially designed for use where the machine is used as a road drag, while the arrangement shown in Figs. 1 and 2 is provided where the machine is to be used as a snow 80 plow.

Arranged at that end of the beam 1 remote from the cross head 2 is a cross head 16 provided at its ends with knuckles 17 to which are connected the wheels 18. Arms 85 19 extend from the knuckles and are connected by a cross rod 20, this rod 20 being adapted to be operated in any suitable manner, as by means of a link 21 connecting it to a disk 22 adapted to be rotated by the 90 steering wheel 23 which is mounted on the same shaft 24 with the disk 22.

Extending forwardly from the head 16 are brackets 25 having the ends of a cross rod 26 secured therein. A lever 27 is fulcrumed on the head 16 and has forwardly extending arms 28 movable therewith, these arms being formed with longitudinal slots 29. Lever 27 is connected by a rod 30 to an actuating lever 31 which may be provided with any suitable means, such as a pawl and segment mechanism indicated generally at 32, for holding it in any position to which it may be adjusted.

An adjustable head shown in detail in 105 Fig. 4, is adapted to be carried by the cross head 16. This adjustable head includes upstanding members 33 having longitudinal slots 34 in their lower end portions through which the rod 26 extends. These upstanding members are connected by a rod 35 which extends through the slots 29 in the arms 28.

Secured to the upstanding members 33 of the adjustable head are upper and lower cross beams 36 and 37 respectively, secured to upstanding side strips 38, the upper beam 36 being likewise secured to longitudinal side beams 39 which come together at opposite sides of a block 40, these blades coming together to form a point below and in advance of the beams 39. The beams 39 and side strips 38 are adapted to be secured to the back faces of large blades 41 constituting the shares of the snow plow and which are preferably formed of heavy sheet metal.

A rod 42 is pivotally connected to the middle portion of the cross beam 36 and to a controlling lever 43 which is similar to the lever 31 and is adapted to be locked in the same manner in any position to which it may be adjusted.

In using the machine, the draft animals are hitched to the trees 12 while said trees are in the positions illustrated in Figs. 1 and 2 and when they are driven forward the plow will be in front of them and will clear a path through the snow. By means of lever 31 the plow can be raised and lowered relative to the beam 1, it being obvious that a rearward pull upon lever 27 will result in the elevation of arms 28 and, consequently, the elevation of the head shown in Fig. 5, the members 33 moving upwardly upon the guide rod 26. When the head is in any position to which it may be adjusted vertically, it can be adjusted angularly by means of lever 43 which, when shifted, will cause the

rod 42 to swing the head about the rod 26, this movement being permissible in view of the fact that arms 28 have the slots 29 therein within which rod 35 can slide.

While the machine is in use the casters 4 are locked against rotation about their vertical axes by the pins 6 and the machine is steered by means of the wheel 23.

It is to be understood that a cutting blade 45 can be located in front of and between the front ends of the blades 41 for loosening packed or crusty snow.

What is claimed is:

The combination with a wheel supported beam having a head at one end, and brackets extending from the head, of a guide connecting the brackets, an adjustable head having upstanding members slidably and pivotally mounted on said guide, road engaging blades carried by the adjustable head and converging to a point, means for swinging said adjustable head about the guide, a lever, a sliding and pivotal connection between said lever and the adjustable head, and means for actuating the lever to raise and lower the adjustable head relative to the head upon the beam.

In testimony that I claim the foregoing as my own, I have hereto affixed my signature in the presence of two witnesses.

PARK G. PAIGE.

Witnesses:

O. H. RYAN,
W. F. MUSOR.
